(57) CLAIM

The ornamental design for a yoga pants, as shown and described.

DESCRIPTION

FIG. 1 is a perspective view of a yoga pants showing the claimed design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof;

The broken lines shown in the drawings depict portions of the yoga pants that form no part of the claimed design.
